UNITED STATES PATENT OFFICE.

HENRY F. SCHMIDT, OF SWARTHMORE, PENNSYLVANIA, ASSIGNOR TO WESTINGHOUSE ELECTRIC & MANUFACTURING COMPANY, A CORPORATION OF PENNSYLVANIA.

EJECTOR.

Application filed November 5, 1920. Serial No. 421,997.

To all whom it may concern:

Be it known that I, HENRY F. SCHMIDT, a citizen of the United States, and a resident of Swarthmore, in the county of Delaware 5 and State of Pennsylvania, have invented a new and useful Improvement in Ejectors, of which the following is a specification.

My invention relates to ejecting devices and it has particular reference to devices 10 employed in exhausting fluid such as air from a receptacle to be evacuated, or in compressing fluid such as air from a region of lower to a region of higher pressure.

An object of my invention is to produce 15 an ejecting mechanism in which means are employed for maintaining the operation of the device substantially constant for practically all varying conditions.

A further object is to produce a steam 20 actuated ejector which is more compact and consequently has a greater capacity for a given size and weight than other ejectors now in use and known to me.

A further object is to produce a steam 25 actuated ejector in which the motive fluid or steam delivery nozzles are so arranged and located that the streams of motive fluid issuing from them combine while traveling in substantially the same direction and 30 thereby eliminate shock and eddy losses which are inherent in other ejectors now in use and known to me.

These and other objects which will be 35 made apparent throughout the further description of the invention are attained by means of apparatus herein described and illustrated in the accompanying drawings in which—

Figure 1 is a vertical sectional view of an 40 ejector embodying my invention.

Figure 2 is a sectional view along the line II—II of Fig. 1.

Figure 3 is a fragmental sectional view 45 corresponding to Fig. 1 and illustrating an arrangement of guide or diffusion vanes which may be employed in the velocity-conversion passage forming a part of the apparatus.

Figure 4 is a sectional view illustrating 50 a modification of construction shown in Figs. 1 and 2.

It has been heretofore proposed to evacuate non-condensable gases from a surface condenser, for example, by means of a two-stage radial-flow type of ejector. The ad-

vantages in the use of this type of evacuating device are marked and are due largely to the energy-transformation taking place in the vortex chamber which remains substantially constant regardless of the volume of fluid delivered, thus producing a uniform efficiency of the ejecting mechanism under widely varying load conditions. A construction embodying this means of evacuating fluids is disclosed in U. S. Patent 60 No. 1,237,219, granted August 14, 1917 to the Westinghouse Electric and Manufacturing Company on an application filed by myself. In this patent, I employ two annular ejectors, a central radial ejector 65 delivering the motive fluid and entrained gases to a surrounding annular ejector to which motive fluid is supplied independently of the motive fluid of the central ejector. The second ejector delivers the mixed fluids to an 70 annular vortex chamber, thence to a volute discharge chamber and to the atmosphere. The present application covers an improvement upon my earlier construction presented 75 in the above mentioned patent and comprises, among other features, a provision of guiding vanes within the vortex chamber, dividing the vortex chamber into a number of diffusion chambers. These vanes are so disposed 80 within the vortex chamber as to correspond to the stream lines which would exist in a free vortex. By this arrangement, the tendency toward upsetting or breaking down 85 of pressure at the discharge portion of the vortex due to eddying of the fluids and to other causes is reduced to a minimum.

The apparatus illustrated consists of a two-stage ejector. The first stage includes an annular nozzle 7, which is adapted to deliver motive fluid in the form of a disc-shaped jet into and through a chamber 8 which is provided with an inlet port 9. The inlet port 9 is arranged to communicate with a condenser or other apparatus to be evacuated. The jet of motive fluid delivered 90 by the nozzle 7, after traversing a free space within the chamber 8, is delivered to an annular diffusion passage 10. Before entering this passage, the fluid traverses an annular combining chamber 11, the converging 100 walls of which are formed by nozzles 12 and 13. The nozzles 12 and 13 are located on opposite sides of the inlet of the annular chamber 10 and both are arranged to deliver disc-shaped jets of motive fluid into 105 110

the passage 10 thus constituting the second stage. Motive fluid, such as steam, is delivered to the nozzle 7 through a port 14 and is delivered to the nozzles 12 and 13 5 through the ports 15, which communicate with an annular steam chamber 16. The annular outlet of the passage 10 communicates with a collecting chamber 17, which may be so constructed as to form a volute 10 chamber having a discharge port 17^a.

The operation of the apparatus is as follows: Motive fluid is delivered to the nozzles 7, 12 and 13. The nozzle 7 is preferably so constructed that it expands the motive fluid 15 traversing it to substantially the pressure normally existing within the chamber 8, and both of the nozzles 12 and 13 are so constructed that they expand the motive fluid traversing them to substantially the pressure 20 encountered at their outlet, or at the inlet to the passage 10. The motive fluid issuing from the nozzle 7, in traversing the free space of the chamber 8, entrains air or fluid to be ejected. The motive fluid and the 25 entrained fluid are subjected to the pressure conversion in traversing the chamber 11. After leaving the chamber 11, the motive fluid discharged from the nozzle 7 and the fluid entrained by it are in turn entrained 30 by the motive fluid delivered from the nozzles 12 and 13, and the mixture of entraining and entrained fluid is then delivered to the 35 passage 10.

In Figure 1, I show the passage 10 provided with separate guide or diffusing vanes 18, which cooperate with each other to divide the passage 10 into a number of diffusion chambers. As illustrated, the vanes 18 are inclined so that they form passages 40 which conform in direction to the line of direction of the fluid issuing from the nozzles 12 and 13, it being understood that the nozzles 12 and 13 are provided with tangential fluid directing vanes 19. It will, of 45 course, be understood that the angle of the vanes 18 may be varied to correspond with variations in the angle of the vanes 19, and that the vanes 18 may preferably be hinged at their inner ends, as at E. If the nozzles 50 12 and 13 are provided with no vanes, the vanes 18 will preferably extend radially.

In Fig. 3, I show the passage 10 provided with spiral vanes 18' of a form corresponding to the stream lines in a vortex. I have 55 also shown these vanes hinged at E so that each is capable of swinging about its hinge and of thereby varying the cross-sectional area of the passage to correspond to the 60 quantity of fluid passing through it. With this arrangement, the ejector is capable of automatically adjusting itself for different rates of flow.

While I have described the apparatus and the several modifications as a two-stage 65 ejector, it will be understood that a single-

stage ejector may be employed which embodies the fundamental principles herein described. For example, the nozzles 12 and 13 may be omitted and the walls of the chamber 8 may be so formed as to provide 70 the convergent combining chamber 11 at the entrance to the passage 10. It will also be apparent that the nozzle 7 may be provided with directing vanes, if desired. In Figure 6, I show a view corresponding to Fig. 1, 75 from which the nozzles 12 and 13 are omitted, and in which the nozzle 7 is provided with tangential vanes for the purpose of imparting a whirling motion to the disc-shaped jet of motive fluid delivered by it. 80

The operation of all forms of my device is substantially the same, and has been sufficiently described with reference to the construction shown in several figures. It is readily apparent from the above description 85 of the construction and mode of operation of the improved ejecting device that a greater stability in the operation of a radial-flow ejector is secured by the provision of guiding vanes in the vortex chamber arranged to conform to the stream lines which naturally exist in a free vortex. This arrangement combines the advantages gained by employing a centrifugal compression chamber and diffusion tubes. Furthermore, the eddying 90 of the streams of radially moving fluid is thereby minimized and a substantial uniform pressure at the peripheral discharge port of the vortex chamber is secured. 95

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims. 100

What I claim is:—

1. An apparatus of the character described comprising, a chamber communicating with a source of medium to be compressed, stationary means for delivering a disc-shaped jet of expansive impelling fluid through a 115 portion of the chamber, stationary means for effecting a compression of the combined media and fluid issuing from said chamber, and adjustable means including stream-line 120 guide vanes for guiding the media and fluid through said compression means. 110

2. An apparatus of the character described comprising, a chamber communicating with a source of medium to be compressed, stationary means for delivering a disc-shaped jet of expansive impelling fluid through a portion of the chamber, stationary means for effecting a compression of the combined media and fluid issuing from said chamber, and pivotally mounted stream-line 125 guide 130

vanes for guiding the media and fluid through said compression means.

3. In an ejector having an annular diffuser, means including stream-line vanes in said diffuser for guiding fluids therethrough and for varying the area of the passage in accordance with variation in the quantity of fluids passing through the diffuser.
4. In an apparatus of the character described, means for effecting a preliminary compression of fluid medium to be expelled, comprising a combining passage in open communication with a source of fluid medium to be expelled, and at least one motive fluid delivery nozzle for expanding motive fluid and for delivering the fluid so expanded into and through said passage, in combination with means for subjecting the fluid medium issuing from said combining passage to further compression, comprising stationary motive fluid delivery means for expanding motive fluid and for delivering
- the fluid so expanded at a high velocity and in the form of a disc-shaped jet, stationary means surrounding said fluid delivery means 25 and in open communication with said passage for receiving the disc-shaped jet of motive fluid and the fluid entrained thereby and for effecting a conversion of the velocity energy of the combined fluid passing there- 30 through into potential energy as represented by an increase in pressure, means including adjustable stream-line vanes for guiding the fluid through said means, a stationary collecting chamber surrounding the last men- 35 tioned stationary means and receiving the fluid discharged therefrom, and means for delivering expansive motive fluid to said nozzle and to said motive fluid delivery means. 40

In testimony whereof, I have hereunto subscribed my name this first day of November, 1920.

HENRY F. SCHMIDT.
